UNITED STATES PATENT OFFICE.

GEORGE A. NOBLE, OF MARYSVILLE, CALIFORNIA.

CONCRETE MOLD.

Application filed March 23, 1922. Serial No. 545,961.

To all whom it may concern:

Be it known that I, GEORGE A. NOBLE, a citizen of the United States, residing at Marysville, county of Yuba, and State of California, have invented new and useful Improvements in Concrete Molds, of which the following is a specification.

This invention relates to concrete molds, such as employed in the erection of walls, buildings and like structures, and especially to a sectional, separable type of mold adapted for hollow wall structures.

Practically all hollow concrete walls and building structures in use today are built up of individually cast hollow concrete blocks, or by temporary wooden frames or molds into which the concrete is poured. Either method or system of construction is almost prohibitive when cost is considered, due to the amount of time and labor required and waste of lumber as the lumber employed for this purpose can seldom be re-used.

The present invention embodies a metal structure by which cost may be considerably lowered; time losses materially decreased, and a rigid hollow wall structure economically obtained. The objects are, to provide an improved and simplified form of mold; a mold which is sectional and which may be readily assembled or removed with relation to the structure; a mold which is permanent and capable of indefinite re-use; a mold which is designed to be raised vertically as the work progresses so that the wall or structure may be cast or poured in as many successive courses as required; and further to provide a temporary frame structure which may be entirely removed when the wall or building is completed, and which will serve as a guide and a partial support for the molds during erection. Other objects will hereinafter appear.

The invention consists of the parts and the construction, combination and arrangement of parts as hereinafter more fully described and claimed, having reference to the accompanying drawings, in which—

Fig. 1 is a plan view of a hollow concrete wall under construction.

Fig. 2 is a cross section of the wall showing the molds in position.

Fig. 3 is a side elevation of the type of spreader employed.

Fig. 5 is an enlarged detail view of the spreader.

Fig. 4 is a cross section on line 4—4, Fig. 5.

Fig. 6 is a perspective view of the channel shaped cap employed in connection with the inner mold.

Fig. 7 is a perspective view of one of the clamps employed.

Fig. 8 is a perspective view of one of the spacing blocks employed.

Referring to the drawings in detail, and particularly to Figs. 1 and 2, A indicates a base or foundation section and B a hollow concrete wall supported thereby. This wall, by referring to Figs. 1 and 2, consists of an outer section 2, a central space or passage 3, and an inner section 4. The inner and outer sections may be cross-tied at intervals, as will hereinafter be described.

The form of mold employed during the erection of the wall structure consists of outer forms or plates such as shown at 5 and 6, and a set of inner forms or plates 7 and 8. The outer mold sections 5 and 6 are in reality nothing more or less than rectangular shaped forms built up of lumber, as shown in Fig. 2, and then placed against the inner and outer sides of the wall where they are held by frame-work hereinafter to be described, and clamps such as generally indicated in Fig. 7. The inner mold is preferably constructed of metal throughout. As previously stated it consists of a pair of inner forms or plates 7 and 8 which may be constructed of fairly heavy sheet iron or the like. These plates are preferably rectangular in shape and may be of any size desired. The plates must be separated and held apart when placed in position on the wall structure and this is accomplished by means of spreaders such as generally indicated in Figs. 3, 4 and 5. The spreaders are arranged in pairs and consist of angle iron bars 9 and 10 connected by links 11 and 12 to a central draw-bar or rod 13, in the upper end of which is formed an eye 14 by which it may be conveniently engaged. The angle bars 9 and 10 have projecting wings and the links 11 and 12, as arranged, form spreaders or toggle links, that

is an upward pull on the draw bar, through means of the eye 14, will cause the angle bars 9 and 10 to approach each other, while a downward movement or push on the draw-bar will cause a spreading action.

To illustrate the use of the molds, and

the method of assembling and supporting the same, we will suppose that the foundation A has been completed and that a section of the wall has also been completed, as indicated at 1, 2, 3, and 4, in Fig. 2. If this section of the wall has set, it is obvious that the molds may be removed and raised to the elevated position shown in the same figure. This is accomplished by removing the clamp generally indicated in Fig. 7. This clamp consists of a pair of legs 17 and 18, which are connected by spreader arms 19 and 20. The leg 17 is hingedly secured to the arm 19, as at 21, while arm 20 is provided with side braces, which are extended as at 22, to form guides for the lower end of the leg 17. The legs 17 and 18 are drawn together when the clamp is employed by means of a rod 23, which is threaded to receive a clamping nut 24. A suitable number of clamps of this character are employed as indicated at C, D and E, when the molds are in position on a wall, as shown in Fig. 1. Each one is of course released and removed when the mold sections are to be elevated. After removal of the clamps, it can be readily seen that the mold sections 5 and 6 may be stripped from the inner and outer surfaces of the wall and that they may be raised to the position shown in Fig. 2; the inner mold sections 7 and 8 being similarly released by drawing upward on the draw bars. To support the inner mold sections 7 and 8, which are in reality nothing more or less than large rectangular shaped sheet-iron plates, one or more cross bars, which are short sections of channel iron, such as indicated at 25, see Fig. 2, are placed on top of the wall section last cast. The sheet iron plates 7 and 8 are then placed on top of these cross bars and are thus secured against downward movement into the hollow space 3 formed between the wall sections. The exterior mold plates or forms 5 and 6 are then placed in position and the clamps applied, after which they are drawn tightly together by means of the rods 23 and nuts 24. The exterior mold sections are so long that they will slightly overlap the wall as indicated at 27 and 28, and will thus bite or tightly engage the wall at this point and downward movement is thus prevented. It is also necessary to maintain a proper spacing between the upper ends of the mold sections and between the said mold sections and the inner sheet iron mold sections. Such spacing is obtained by inserting spacer bars 30 as shown in Fig. 8. Insertion of the spreaders, such as shown in Figs. 3, 4 and 5, will insure perfect positioning and spacing of the inner molds. A cap or channel shaped plate such as shown at 31, see Fig. 6, is finally placed on top of the inner mold sections and the concrete may then be poured into

the spaces indicated at 32 and 33, see Fig. 2, until the spaces have been completely filled. The concrete will then remain until partially set, when the clamps may again be removed and the molds stripped from their respective surfaces, after which they may again be elevated and the structure carried to any height desired.

By referring to Fig. 1 it will be noted that a temporary frame structure is employed in connection with the exterior molds 5 and 6. The exterior frame in reality is nothing more or less than vertically disposed studs, as indicated at 40, 41, 42 and 43. The type of stud indicated at 40 is employed at all interior corner intersections; the type of stud illustrated at 41, where flush or parallel surfaces are encountered, and the type of stud 43 is employed at all exterior corner sections. By referring to the several types of studs employed, it will be noted that they are all notched or channeled to receive the exterior mold sections 5 and 6, and they thus form vertical guides for the same, which maintains such alignment as required. Where window or door frames are required, it is only necessary to insert them between the exterior mold sections as the work is proceeding; a type of window frame conveniently employed being that indicated at 50, and a suitable type of door frame that indicated at 60. These features however form no particular part of the present invention and they are therefore merely incidentally disclosed.

The present invention involves several important features, first of all, it can be seen that the spreaders illustrated in Figs. 3, 4 and 5 are constructed of metal throughout and as such may be subjected to a great deal of wear and abuse without danger of destruction. The inner mold plates or forms are preferably constructed of sheet iron and as such should also be indestructible. The exterior molds or plates 5 and 6, while here illustrated as constructed of lumber, may also be formed of metal sheets, if desired, or they may be lined with galvanized iron where conditions may demand. The molds are therefore permanent and may be used over and over, not only on one building, but where a series of buildings are to be erected. This is of great importance as it materially reduces the general cost of construction when comparison is made with many structures erected today where wood forms are employed, and where the lumber must be stripped off and thrown away when the work is completed.

The clamps generally indicated in Fig. 7 are of the permanent type, as are also the studs shown at 40, 41, 42 and 43. These studs may be constructed of a fair grade of lumber and may be oiled or otherwise

treated to render them as permanent as possible. They may therefore also be re-used on one job or building after another. The use of these studs is an important feature 5 of the present invention as it provides a partial support and guide for the molds, and above all insures perfect alignment of the same during the entire building operation. The studs may be pressed or tied together 10 in any suitable manner, not here shown. All parts are used over and over again, thereby eliminating waste, and as the molds may be quickly and readily assembled or stripped with relation to the work, it is 15 obvious that practically little time and labor will be required for this purpose, thus further increasing the economy of such structures.

While certain features of the present invention are more or less specifically illustrated, I wish it understood that various changes in form and proportion may be resorted to within the scope of the appended claims, similarly that the materials and 25 finish of the several parts employed may be such as the experience and judgment of the manufacturer may dictate or various uses may demand.

Having thus described my invention, 30 what I claim and desire to secure by Letters Patent is:—

1. A mold for constructing hollow concrete walls, said mold comprising inner and outer rectangular shaped plate-like forms, 35 cross bars having shoulders formed thereon engageable with the inner and outer mold plates to maintain a predetermined spacing between the same, spreader members interposed between the inner forms, clamping 40 members engaging the exterior forms, vertical guides for the outer forms in which said forms are vertically movable, and means on the clamps supporting the clamps and outer forms with relation to the inner forms.

45 2. A mold for use in constructing hollow concrete walls, said mold comprising rectangular shaped plate-like forms, and said

forms comprising an outer pair and an intermediate pair of forms, means on the wall structure proper for supporting the intermediate forms, spreader members interposed between the inner forms and maintaining a predetermined spacing between the same, spacing bars interposed between the intermediate forms and the outer forms and 50 maintaining a predetermined spacing between the same, U-shaped clamping members engageable with the exterior forms and clamping rods passing through the U-shaped clamps to tighten the same, said rods 55 engaging the intermediate forms and supporting the exterior forms and the clamps with relation thereto.

3. A mold for constructing hollow concrete walls, said mold comprising inner and outer 60 plates and clamps each clamp composed of vertical legs engaging the outer plates, horizontal arms arranged at the upper ends of the legs and at an intermediate point and rigidly secured to one of the legs, the other 70 leg being hinged at its upper end to the top arm, a guide carried by the other arm and receiving the hinged leg and an adjusting rod connecting the legs and arranged below the arms and arranged to rest upon the said 75 plates for supporting the clamp in position.

4. A mold for constructing hollow concrete walls, said mold comprising inner and outer plates and clamps each clamp comprising vertical legs engaging the outer 80 plates, spaced horizontal arms located at the upper ends of the legs and at an intermediate point and rigidly secured to one of the legs, the other leg being hinged at its upper end to the top arm, side braces arranged at the 85 side faces of the other arm and secured to the same and to one of the legs and projecting beyond the said arm and forming a guide for the hinged leg and an adjusting rod located beneath the arms and connecting 90 the legs and arranged to rest upon the said plates for supporting the clamp.
